UNITED STATES PATENT OFFICE.

JOSEPH BAILEY NESBIT, OF SUNBURY, PENNSYLVANIA, ASSIGNOR OF ONE-HALF TO PETER P. SMITH, OF SAME PLACE.

TUMBLER-WASHER.

SPECIFICATION forming part of Letters Patent No. 579,600, dated March 30, 1897.
Application filed March 25, 1896. Serial No. 584,804. (No model.)

To all whom it may concern:

Be it known that I, JOSEPH BAILEY NESBIT, a citizen of the United States, residing at Sunbury, in the county of Northumberland and State of Pennsylvania, have invented 5 certain new and useful Improvements in Tumbler-Washers, of which the following is a specification.

This invention relates to improvements in 10 that class of tumbler-washers in which brushes are carried within a revolving casing for the purpose of washing drinking-glasses, such as are used at bars and soda-fountains.

The present invention consists in various 15 improvements in the details of construction of such tumbler-washers, a full, clear, and exact description of which will be found in the following specification, reference being had to the accompanying drawings, in which— 20 Figure 1 is a side view of the tumbler-washer in operative position. Fig. 2 is a longitudinal central sectional view, and Fig. 3 is a cross-section taken on the line 3-3 of Fig. 2.

Referring to the drawings, 1 indicates a 25 cylindrical casing which is closed at the end 2 and partially closed at the opposite end by an inturned flange 3, and having a large central opening 4, through which the glasses may be inserted to be washed. This tumbler-washer is intended to be used with a suitable 30 motor. In the drawings I have shown a water-motor 5, attached to a support 6, the water being supplied through a pipe 7 and discharged through the pipe 8. The pipe 7 is 35 provided with a valve 9 for starting and regulating the speed of the motor. In some instances I may use an electric or other motor, but where practicable water will be most economical, for the reason that the same water 40 which runs the motor may be used to rinse the glasses.

The casing of the tumbler-washer is mounted 45 on a shaft 10 of the motor in the following manner: A hub 11 is provided with a socket 12, into which the end of the shaft fits, and a set-screw 13 for clamping the hub on the shaft, the set-screw having a long stem, the outer end of which is supported in a bracket 14 on the end of the casing, and a handle 15, 50 which projects beyond the casing. This enables me to attach and detach the casing

quickly and conveniently. Upon the opposite end of the hub there is a projecting spindle 16, having a screw-threaded portion 17. The threaded portion passes through a 55 central hole in the end 2 of the casing, and the casing is clamped to the hub by means of a washer 18 and nut 19, as shown in Fig. 2.

There is a central brush 20, the stem of 60 which is provided with a sleeve 21, adapted to fit the end of the spindle 16. The brush 20 is thus held centrally in the casing of the washer, and at the same time it can be quickly removed. For washing large glasses I use a large central brush and attach side brushes 65 directly to the wall of the casing. As shown, there are two of these brushes 22, each consisting of a pair of wires wound together spirally with bristles clamped between them. One end of each brush is held in a loop or 70 staple 23, and the other end by a hook 24. These side brushes can be very quickly placed in position simply by inserting one end of the wire in the loop 23 and passing the other end into the hook 24. 75

For washing small glasses I remove the central brush and place a smaller brush on the spindle 16. In order to be able to use the same-sized brushes on the sides for either large or small glasses, I sometimes attach 80 brackets 25 to the inner wall of the casing 1, and upon these brackets the brushes 22 can be supported by means of loops 23 and hooks 24. Brushes for washing small glasses are indicated by dotted lines in Fig. 3. When it 85 is desired to wash small glasses, the brushes which are attached directly to the casing need not be removed, it being simply necessary to attach the brushes to the brackets 25. When larger glasses are to be washed, the 90 brushes are removed from the brackets 25, and a large central brush mounted on the spindle 16.

The operation is as follows: The brushes are placed in position, as shown in Figs. 2 95 and 3, and the washer is mounted on the shaft of the motor, as shown in Fig. 1. The valve 9 is then opened, and the cylinder and brushes begin to revolve. A little water is taken into the glass and thrown into the cylinder, and 100 the glass is then inserted through the hole 4 until the central brush extends to the bottom

of it. The revolution of the cylinder will distribute the water over the brushes, and any dirt or liquid adhering to the glass will be quickly loosened. The glass is then removed and rinsed with water, which may be obtained from the discharge-pipe of the motor. When the washer becomes foul, it can be quickly removed by loosening the thumb-screw 13, and the interior can be thoroughly rinsed out without removing the brushes.

The casing may be made of galvanized iron or other sheet metal at very slight cost. I have adapted the washer for the use of brushes composed of bristles clamped in spirally-wound wire, and such brushes can be obtained at a very low cost, so that the expense of renewing them is inconsiderable. On these brushes the bristles surround the wire, and when they are attached to the sides of the casing the bristles on one side are flattened out and they serve as springs to hold the brush tightly in its fastenings. The central brush can be formed by bending one of these wire-core brushes around a central stem, as shown.

Having described my invention, what I

claim, and desire to secure by Letters Patent, is—

1. In a tumbler-washer the combination with a cylindrical casing, of a central spindle fixed to one end thereof, a central brush removably connected with said spindle, and side brushes removably connected to the inner wall of the casing, one end of each side brush being inserted in a loop and the other end in a suitable hook, substantially as described.

2. In a tumbler-washer, the combination with the cylindrical casing rotatably mounted upon a shaft, of the central spindle and the central brush detachably mounted on said spindle, inwardly-projecting brackets on the interior of the casing, side brushes, and means for attaching said side brushes to the walls of the casing and to said inwardly-projecting brackets, substantially as described.

In testimony whereof I affix my signature in presence of two witnesses.

JOSEPH BAILEY NESBIT.
